BOXMAKING MACHINE

George S. Sillars, Beverly, Mass., assignor to
 Hoague-Sprague Corporation, Lynn, Mass., a
 corporation of Massachusetts

Application May 6, 1948, Serial No. 25,460

5 Claims. (Cl. 93—49)

1

This invention relates to machines for making boxes and is illustrated as embodied in a machine of the type in which an operator successively presents opposite ends of a box blank to box forming mechanisms. An object of the invention is to provide improved mechanism of simple construction by which a box blank is formed into a completed box.

As illustrated herein, a box blank, the side wings of which have been folded at right angles to the bottom, is presented bottom face up to a member by which the corner laps are folded inwardly toward each other and is then presented to mechanism by which glue is applied to an end wing which lies in the plane of the box bottom. The blank is then moved by the operator past a folding member which operates to turn the end wing down at a right angle to the bottom of the box and into contact with the corner laps. The corner lap folding, gluing, and end wing turning instrumentalities are illustrated as similar to those shown in Letters Patent of the United States No. 2,186,977, granted January 16, 1940, on an application filed in the name of C. D. Knowlton. After the end wing has been turned into contact with the corner laps the partially completed box is presented to a combined end wing extension folding member and box end pressing mechanism, the box being turned into a vertical position by the operator with the end of the box to be completed uppermost.

The end wing extension folding member comprises a vertically disposed plate having a rearwardly inclined lower portion against which the end wing extension is pressed by the operator, the extension being bent inwardly by pressure thereagainst. The box is then moved upwardly over the plate, causing the end wing extension to be bent at a right angle to the end of the box, this movement continuing until the box end clears a form or anvil mounted at the upper end of the plate whereupon the box is moved rearwardly by the operator so that the end wing extension is bent against the inside of the box end and the end is supported by the anvil. A movable press member is then moved downwardly and in cooperation with the anvil presses together the parts forming the end of the box.

In accordance with a feature of the invention the operation of the press member is initiated by pressure exerted through the bottom of the box by the operator against the end wing extension folding plate. Thus the press member is operated upon movement of the box into the proper position for the application of pressure to the end

2

thereof. By thus controlling the operation of the press member correct positioning of the box for the pressure-applying operation is assured irrespective of the size or height of the box.

5 The above and other features of the invention including various details of construction and novel combinations of parts will now be described by reference to the drawings and pointed out in the claims.

10 In the drawings,

Fig. 1 is an angular view of one form of machine in which the invention is embodied;

Fig. 1a is a plan view of one form of box blank upon which the machine is designed to operate;

15 Fig. 2 is an elevation, partly in section, of the clutch and actuating mechanism therefor, by which operation of the press is controlled;

Fig. 3 is a side elevation, partly in section, of the mechanism for pressing the end of the box;

20 Fig. 4 is a front elevation, partly in section, of a brake associated with the drive shaft of the press;

Figs. 5, 6 and 7 are side elevations of the press members illustrating different positions of the 25 box as it is presented thereto for a pressing operation; and

Fig. 8 is a plan view of the anvil of the press illustrating the operation of the member by which the press is controlled.

30 One form of box blank upon which this machine is adapted to operate is illustrated at 8 in Fig. 1a and includes side wings *a*, end wings *b*, corner laps *c* and end wing extensions *d*. In forming the blank into a box, the side wings *a*, which are separated from the body of the blank by creases, are folded at right angles to the body of the blank and the corner laps *c* are then folded inwardly at right angles to the side wings. After glue has been applied to the inner face of the

35 end wings *b*, they are bent into engagement with the adjacent faces of the corner laps and the end wing extensions *d* are then folded over against the inner faces of the corner laps to form a completed box. In operating upon a blank with the present machine each end of the box is treated separately and pressure is applied to one end of the box after the completion of the operations outlined above to unite the component parts of the box end into a single unit.

40 The machine includes, as its essential elements, a corner lap folder *A*, gluing mechanism *B* for applying glue to the end wing of the box blank, a folder *C* by which the end wing is folded against the corner laps, an end wing extension folder *D*, and a press *E* by which the parts

forming the end of the box are pressed together.

The corner lap folder A comprises a curved plate 10 against which the forwardly extending corner laps c, of a box blank, the side wings a of which have been turned at right angles to the bottom of the box, are pressed and turned inwardly toward each other as illustrated more particularly in the Knowlton patent referred to above. The plate extends lengthwise of the machine past the gluing mechanism B and terminates just short of the end wing folder C. The upper edge of the plate 10 forms a guide for supporting the end wing in the plane of the bottom of the box which is held uppermost as the box is presented by the operator to the gluing mechanism and end wing folder.

The gluing mechanism B comprises a gluing roll 12 carried by a shaft 14 journaled in bearings 16 carried by the frame of the machine and the top of the roll 12 lies substantially in the same horizontal plane as the upper edge of the plate 10. The shaft 14 is connected by gears 18, 20 to a shaft 22 carrying at its forward end a glue transfer roll 24 which transfers glue from a pot 26 onto the gluing roll 12. A roll 28 carried by a shaft 30, urged downwardly by springs 32, is arranged to hold the end wing of the box in contact with the gluing roll 12. Guide plates 34, 36 guide the entering end wing into the bight of the rolls 12, 28. Suitable driving mechanism, not shown, is connected by a bevel gear 38 to the shaft 22 to rotate the rolls 12, 24 constantly during the operation of the machine.

Located just beyond the end of the plate 10 in the path of movement of the box by the operator is the end wing folder C which is in the form of a scroll-shaped plate 40 having a curved surface 42 which deflects the end wing from its horizontal position to a substantially vertical position so that it approaches and contacts with the outside of the corner laps of the box. The corner lap folder A, gluing mechanism B and the end wing folder C are substantially like the corresponding elements illustrated and described in the Knowlton patent to which reference may be had for a more complete description and explanation thereof.

After the end wing has been folded into contact with the corner laps the box is then turned into a vertical position, as shown in Fig. 5, with the end wing extension d which extends above the top margin of the box in the plane of the end wing, in contact with a vertically disposed plate 46 having a downwardly and rearwardly inclined portion 48. This plate is carried by a rearwardly extending rod 50 which is slidable in the frame of the machine and passes through a supporting block 52 for an anvil 54. A light spring 56 seated in a recess in the forward portion of the supporting block 52 maintains the plate 46 in a position spaced slightly from the block as shown in Figs. 5, 6 and 7 for a purpose to be described. This spring is strong enough so that movement of the box upwardly with the end wing extension in contact with the plate will not cause rearward movement of the plate. As the operator moves the box into contact with the lower end of the plate 46 and then upwardly over the surface of the plate, the end wing extension is first turned into an inclined position, as shown in Fig. 5, and then is turned into a position at right angles to the end wing, as shown in Fig. 6. After the box has moved upwardly a sufficient distance so that the end wing clears the anvil 54 the box is moved rearwardly so that the end of the box occupies a position between the anvil and a press member 58. The

press member 58 projects forwardly of the anvil 54 and acts as a stop in the upward movement of the box. This rearward movement of the box causes the end wing extension to be turned into the position shown in Fig. 7 to be pressed against the inner faces of the corner laps. To accommodate the increased thickness of the box end at its top margin, occasioned by the end wing extension, the rear portion of the anvil is recessed at 60 so that when the press member 58 moves downwardly into the position shown in Fig. 3 substantially equal pressure will be applied throughout the entire end of the box.

The upper press member 58 carries an upwardly extending stem 62 from the upper end of which projects a radially extending pin 64 which passes through vertical slots 66 formed in the lower portion of a U-shaped slide 68. This slide is mounted for vertical movement in a slideway formed by plates 70, 72 (Fig. 1) secured to the frame of the machine, the frame of the machine also providing the inner portion of the slideway. Springs 74 (only one of which is shown) connected between the top of the press member 58 and the plates 72 act to maintain the press member 58 with the slide 68 in the elevated position as shown in Figs. 5 to 7 with the press mechanism at rest. A heavy spring 76 is positioned between the top face of the press member 58 and the under face of the slide 68 so that the press member and the slide are normally held apart to the extent permitted by the engagement of the pin 64 with the material of the slide at the bottom of the slot 66. This spring, however, permits downward movement of the slide relatively to the press member so that the press member acts upon the box end with a yielding pressure.

Located between the front and rear portions of the slide 68 is a roll 78 journaled on a shaft 80 carried by the slide. This roll is held by the springs 74 (Fig. 1) in contact with a cam 82 secured to the forward end of a shaft 84 journaled in the top of the machine frame. With the press mechanism at rest the roll 78 engages a low portion of the cam 82 but upon rotation of the shaft 84 the cam 82 forces the roll 78 with the slide 68 downwardly to move the press member 58 into engagement with the end of a box supported by the anvil 54. The cam 82 is so shaped, as shown in Fig. 1, that the end of the box is held under pressure during the greater part of a revolution of the shaft 84.

For driving the shaft 84 during a pressing operation, mechanism shown in Figs. 1 and 2 is provided. Journaled on the rearward end of the shaft 84 is a gear 86 having a forwardly extending hub portion 88 which surrounds but is spaced from the adjacent portion of the shaft 84. Engaged with the gear 86 is a pinion 90 on a shaft 92 which may be constantly rotated by any suitable mechanism so that the gear 86 is maintained in constant rotation. Keyed to the shaft 84 is a cam 94 having its periphery formed with a series of flat surfaces, between which and the hub portion 88 of the gear 86 is located a race 96 carrying a series of rolls 98. When the cam 94 is turned in a clockwise direction, as viewed in Fig. 2, from the position shown, relatively to the race 96, the rolls 98 are wedged between the flat surfaces of the cam 94 and the interior of the hub 88 whereupon the gear 86 is connected to the shaft 84 to drive the shaft. The race 96 is provided at its forward end with a circular flange 100 having a radial keyway 102 in which is slidably a key 104 connected by a pin 106 with a trip cam

108 having a loose fit on the shaft 84 journaled forwardly of the flange 100. The trip cam 108 is pivoted at 110 to a plate 112 keyed to the shaft 84. A spring 114, connected between a pin 116 carried by the plate 112 and a pin 118 carried by the trip cam urges the trip cam in a direction relatively to the shaft 84 to move the cam 94 in a clockwise direction. The trip cam 108 has a shoulder 120 arranged at the completion of one revolution of the shaft 84 to engage a latch 122 whereupon the trip cam is moved against the action of the spring 114 relatively to the shaft 84 in a counterclockwise direction about the pin 110 causing the cam 94 to return to the position shown in Fig. 2 disengaging the gear 86 from the shaft 84. As soon, however, as the latch 122 is moved away from the shoulder 120 the clutch is re-engaged causing rotation of the shaft 84 and downward movement of the upper press member 58. It will be understood that any suitable form of one-revolution clutch may be substituted for the one shown herein.

The latch 122 is carried by a lever 124 pivoted at 126 to the frame of the machine and urged by a spring 128 into engagement with the periphery of the trip cam 108. The lever 124 is moved in a clockwise direction when it is desired to operate the press mechanism. For this purpose the right end of the lever 124 is connected by a link 130 to an armature 132 of a solenoid 134 which when energized causes the armature 132 to be drawn inwardly, rocking the lever 124 in a clockwise direction.

The solenoid 134 has in its circuit a normally open switch 136 having a button 138 arranged when the button is depressed to close a circuit through the solenoid 134 initiating operation of the press member 58. The button 138 is located in alignment with the rod 50 and upon the application of pressure to the plate 46 sufficient to overcome the spring 56 the rod 50 engages the button 138 closing the switch 136. For thus moving the plate 46 the operator applies pressure thereto through the bottom of the box as illustrated in Fig. 8 when the box end is positioned on the anvil 54.

In order to insure that the shaft 84 will stop upon disengagement of the clutch a friction brake 140 (Fig. 4) is provided. This brake includes a band 142 which substantially surrounds the shaft 84, one end of the band being connected to a rod 144 which passes loosely through a pin 146 connected to the other end of the band 142. The pin 146 passes through an extension 148 (Fig. 1) of a bearing 150 for the shaft 84. The outer end of the rod 144 is threaded to receive a nut 150 which forms an abutment for one end of a spring 152 the other end of which engages the adjacent end of the brake band. By turning the nut 150 the action of the spring 152 is varied to vary the braking effect of the band 142 which is adjusted so that the shaft 84 will come to rest immediately upon disengagement of the clutch.

In the operation of the machine, the operator takes a flat box blank and bends the side wings *a* down and then presents the corner laps *c* at one end of the box blank to the wall 10, bending the corner laps inwardly with the end wing *b* extending over the top edge of the wall. The box is then carried by the operator along the wall, the end wing passing between the rolls 12, 28 whereupon glue is applied to the inner face of the end wing. The end wing is then turned downwardly by the scroll-shaped plate 40 into engagement with the outer faces of the corner laps after which

the box is turned into a vertical position and the end wing extension *d* moved into contact with the lower end of the plate 46, as shown in Fig. 5, to start turning the end wing extension inwardly. The box is then moved upwardly as indicated in Figs. 6 and 7 until the end of the box engages the under surface of the forward portion of the press member 58, whereupon the box is moved rearwardly as indicated in Fig. 7 until the bottom of the box engages the plate 46. The box is now positioned for the application of pressure to its end and operation of the pressure applying mechanism is initiated by the operator, as indicated in Fig. 8, by applying pressure, preferably with the thumbs, through the box bottom against the plate 46 which thereby functions as a trigger. It is necessary only to apply momentary pressure to the plate 46 sufficient to energize the solenoid 134 and withdraw the latch 122 to permit engagement of the clutch. The shaft 84 now rotates through one revolution and, providing that the operator has released pressure on the plate 46 permitting the solenoid to be de-energized, the clutch will be disengaged upon movement of the shoulder 120 of the trip cam 108 into engagement with the latch 122.

By controlling the operation of the pressure applying mechanism by pressure applied through the bottom of the box it will be understood that the box will always be correctly positioned for the application of pressure to its end regardless of the height of the box. The same trip may be employed without the necessity of making any adjustments for applying pressure to the ends of box covers as well as boxes inasmuch as the end of the cover will be properly positioned for the application of pressure when the top of the cover is brought into position against the plate or trigger 46.

Having thus described the invention, what I claim as new and desire to secure by Letters Patent of the United States is:

1. In a box-making machine, relatively movable press members engageable with the inner and outer faces of the end of a partially formed box, power-operated mechanism for moving one of the said press members toward the other to apply pressure to said faces, and a trigger adjacent to said press members for initiating operation of said mechanism, said trigger being positioned to lie within the box for actuation by pressure exerted through the bottom of the box upon movement of the box into position for engagement by said press members.

2. In a machine for making boxes from blanks having end wings and end wing extensions, relatively movable press members engageable with the inner and outer faces of the end of a partially formed box, power-operated mechanism for moving one of said press members toward the other for applying pressure to said faces, a plate associated with said press members in contact with which the end wing extension is moved to bend the extension inwardly of the end wing, said plate being positioned to lie within the box and to be engageable by the bottom of the box when the end of the box is properly positioned between said press members, means mounting said plate for movement by force applied thereto by the operator through the bottom of the box, and means operated by said plate in response to such movement for controlling said mechanism.

3. In a box-making machine, relatively movable press members engageable with the inner

and outer faces of the end of a partially formed box, power-operated mechanism for moving one of said press members toward the other for applying pressure to said faces, a clutch for controlling said power-operated mechanism, a solenoid arranged upon energization thereof for causing engagement of said clutch, a switch in the circuit to said solenoid, and a trigger for closing said switch, said trigger being positioned to lie within the box for actuation by pressure exerted through the bottom of the box as the box is brought into position for engagement by said press members whereupon said clutch is engaged and pressure is applied to the end of the box.

4. In a machine for making boxes from blanks having end wings and end wing extensions, an anvil upon which the inner face of the end of a box is supported for a pressing operation, a horizontal press member above said anvil movable downwardly to press the end of the box, power-operated mechanism for thus moving said press member, a vertical plate below the forward edge of said anvil and positioned to lie within the box for engagement by the bottom of the box when the end of the box is positioned on said anvil for the pressing operation, means mounting said plate for rearward movement upon application of pressure thereto by the operator through the bottom of the box, and means operated in response to rearward movement of said plate for controlling said power-operated mechanism.

5. In a box-making machine, an anvil for supporting the inner face of the end of a partially completed box, a press member above said anvil movable toward it for applying pressure to the end of the box, power-operated mechanism for thus moving said press member, a clutch in control of said power-operated mechanism, a solenoid, means operated upon energization of said solenoid for engaging said clutch, a plate below the forward edge of said anvil positioned to lie within the box for engagement by the bottom of the box when the end of the box is properly positioned on the anvil for the pressure-applying operation, means mounting said plate for rearward movement upon the application of pressure thereto by the operator through the bottom of the box, a switch in the circuit to said solenoid, and means operated by said plate in its rearward movement for closing said switch.
